(57) **CLAIM**

The ornamental design for an interlocking toy, as shown and described.

DESCRIPTION

FIG. 1 is a perspective view of the interlocking toy in accordance with a first embodiment of the present invention;

FIG. 2 is a top view of the interlocking toy of FIG. 1, the bottom view being the same; and,

FIG. 3 is a first side view of the interlocking toy of FIG. 1, each of the four side views being the same.
